UNITED STATES PATENT OFFICE.

GEORGE W. EDWARDS, OF TOLEDO, OHIO.

AUTOMATIC TRAIN-CONTROLLING APPARATUS.

Application filed April 17, 1922. Serial No. 553,560.

My invention relates to automatic train controlling apparatus, and has to do with the provision of novel control devices which, cooperating with the air brake equipment of the train, will not only positively control and stop the train in conditions of extreme danger but which will stop also, in normal operation, effectually and automatically stop the train within definite safety limits from any danger or block point. It also results in important safety measures in that the train is positively protected at all times from danger of rear end collisions.

My invention has to do primarily with the provision of means for positively releasing the air in the air brake system of a train so as to insure a positive stopping of a train at a safe distance from any point of danger. This is accomplished by means of very simple and compact structures which comprise electrically controlled means carried by the train and operated by striking a charged ramp or third rail; means for automatically charging said rail in the event of track or closed block danger, and governor controlled means also carried by the train for charging a fourth and third rail system. The third rail in all cases is preferably connected to a current supply only in case of track or train danger or the stopping of the train by a closed block.

One of the objects of my invention is the provision of a solenoid operated valve which is adapted to be easily connected to the air brake system of the train and which is electrically connected to the truck wheels and to a trolley also carried by the train and so arranged that when the trolley strikes a charged third rail, or a third rail connected with a source of current supply, the solenoid will be so energized as to positively operate the valve. The result is that the train will be positively stopped whenever this trolley strikes a third rail that is connected with any source of current supply and also with a rail of the main track.

A further object of my invention consists in providing differential area surfaces for my solenoid operated valve, and which will cause this valve to remain normally closed due to pressure from the brake pipe system, and which will be positively opened by actuation of the solenoid core, the said valve being so designed that when once opened it

will remain open until manually closed. In this case the train will be positively stopped and will remain at a standstill until the engineer or some one from the train descends from the train to the ground to manually close the valve and thus release the brakes. Furthermore, I have provided means in connection with the solenoid valve that will insure a report of the cause of every automatic stopping of the train due to the operation of the solenoid valve.

A still further object of my invention has to do with the provision of a switch or contactor in connection with a regular track switch and which is so arranged as to connect a third rail and a track rail with a current supply whenever the switch is open for any cause whatever, but which will disconnect the third rail from the current supply whenever the switch is closed. In this case, it will be evident that the third rail will be charged and the train stopped whenever the switch is accidentally left open or whenever the switch is broken or is forced open by reason of pebbles or other common means.

Another object of my invention consists in providing a contactor similar to the track switch contactor but which is preferably connected with the regular track semaphore system, and which is so arranged as to connect the track rail and an appropriately placed third rail with a source of current supply whenever a semaphore or a multiple semaphore system is in closed block or danger position. This source of current supply may be a single source of current supply for any number of semaphore signals or track switch contactors within a limited vicinity.

I have further provided means for supporting and pivoting the train trolley whereby the trolley, in case the train is going forward, will be so tripped by a charged third rail as to positively actuate the solenoid valve but which, in case the train is going backwards, will be tripped in the opposite direction upon striking the third rail so as not to energize the solenoid. For example, if a train in switching passes a third rail connected with an open semaphore this semaphore will be automatically changed to danger position and the third rail charged, and when the train is backed up past this charged third rail the trolley will be tripped

into nonoperative position so as to allow the train to back past the third rail without setting the brakes.

Still another object of my invention has to do with the provision of a series of fourth rails, preferably placed in between the third rail and the standard track rail, and governor controlled means carried by the train for connecting said fourth rails and a rail of the track with a current supply also carried by the train. Furthermore, I have provided fourth rails of a definite length and have so connected each of said fourth rails with a separate third rail and so placed with relation to its respective fourth rail that when the fourth rail is charged by a current supply from the train this current will be conducted along the fourth rail and to the third rail for a sufficient distance to energize the solenoid and stop any oncoming train that would normally crash into the rear of said first named train. Thus, if a train is stopped at any place, for example, the station stop, or if a slow freight passes by a block which is accidentally stuck, the third rails for a definite distance back of the train will be so successively charged as to positively stop any oncoming train that would strike this charged third rail.

Many other features of my invention will be apparent as this description progresses and will be brought out in the claims appended hereto. The various objects of my invention are preferably obtained by the structures illustrated in the drawings, wherein in similar characters of reference designate corresponding parts, and wherein

Figure 1 is a fragmentary side elevation of a locomotive and showing a third rail, a pivoted trolley and a solenoid operated valve in proper relation to the trolley and the air brake system of the train.

Figure 2 is an enlarged detail view showing my contactor mechanism for connecting a semaphore system with a source of current supply and with the track and the third rail.

Figure 3 is an enlarged vertical sectional view of my solenoid operated valve showing the differential surfaces for normally keeping the valve closed and the toggle mechanism for opening the valve upon actuation of the solenoid core.

Figure 4 is a detail plan view showing my contactor mechanism controlled by a track switch for connecting a third rail and a track rail with a current supply when said switch is open.

Figure 5 is a plan view of a track provided with third rails and contactor mechanism for connecting the third rails with a current supply and also showing, in elevation, semaphore apparatus for operating the contactor mechanisms.

Figure 6 is a plan view of a standard

track and track switch and showing the method of connecting my contactor mechanism to one arm of the switch and also showing the manner of connecting the contactor contacts with a track rail and a third rail. 70

Figure 7 is a plan view of a standard track equipped with a series of fourth and third rails, and showing the manner of connecting the fourth rails with alternate third rails and also showing the manner of connecting a semaphore or switch contactor with a separate third rail and with the track. 75

Figure 8 is a diagrammatical end elevation of my governor controlled trolley mechanism as preferably attached to the rear end 80 of a train and also showing the method of connecting the fourth rail with a current supply from the train.

In the drawings, my invention is shown as comprising a solenoid operated valve 1 connected through a pipe 2 to the air brake pipe system 3 of the train. This solenoid operated valve, as best shown in Figure 3, preferably comprises a casing 4 with an attached solenoid 5 and an orifice 6 for the reception of a stem 7 of the solenoid core 8. This solenoid stem 7 is slotted as at 9 to receive the joint of the toggle levers 10 and 11. The upper toggle lever 10 is pivoted as

at 12 and the lower toggle lever 11 is pivotally connected to the top of a valve stem 13. The lower end of this valve stem 13 is provided with a valve 14 designed to be seated on the valve seat 15 of the casing 4 and the upper end of this valve stem is provided with a plate 16 and an elastic disk or surface 17 preferably secured by the joint 18 formed by the casing 4 of the valve. This upper plate 16 is preferably of a larger area than the lower valve 14 whereby the compressed air of the air brake system entering through the inlet 19 will normally hold the valve 14 on its seat by reason of the resulting differential pressure. The valve 14 when lowered by the inward action of the solenoid core 8 100 obviously remains open in this position until the solenoid stem 7 is manually pulled outward. 105

The solenoid 5 is connected to a truck axle 20 by means of a connecting wire 21, as 115 diagrammatically shown in Figure 1. The other pole of the solenoid is connected to a contact finger 22 by means of a suitable connecting wire 23. This contact finger is insulated from and secured to an arm 24 suitably mounted to the engine frame and adapted to pivotally support a trolley 25. This trolley 25 is vertically adjustable by means of a turnbuckle 26 and so pivotally connected to the arm 24 that it will contact with and be 120 swung back rearwardly by a third rail 27.

This third rail 27 is of such construction that it will preferably extend above the standard rail 28 and is desirably located outside of the standard rail as clearly shown 125 130

in Figures 1 and 8. The base of the third rail 27 is secured to the ties of the track in the usual manner and the ends of the top of the rail are preferably chamfered as at 29 5 in order to lessen the impact when the trolley 25 strikes this third rail. The third rail is also of such height that it will swing the trolley 25 rearwardly so as to make a positive contact with the contact finger 22, and 10 the third rail is of a sufficient length that the trolley will be held in this tripped position long enough to insure a positive energizing of the solenoid and actuation of the 15 solenoid core 8. In the backward movement of the train the trolley 25 will again strike the third rail 27 but it will be swung in the opposite direction out of contact with the contact finger 22.

As shown in Figures 1, 5 and 6, the third rail 27 is connected to a battery or source of current supply 30 and to one contact 31 of a contactor switch 32. As shown in Figures 2 and 5, this contactor 32 may be supported by a single semaphore post 33 or a multiple 25 semaphore post 34, and comprises two contactor posts 31 and 35 which are held in upper position by means of the springs 36 acting on the contactor heads 37 and 38 of the contacts 31 and 35, the contacting head 30 37 being connected to the battery 30 and the third rail 27 and the contact head 38 being connected to one of the standard rails 28 of the track. Located above the two contacts 31 and 35 and adapted to be vertically reciprocated within the casing of the contactor 32 35 is a switch arm 39. This switch arm 39 is preferably insulated as at 40 and is provided with a guiding rod 41 and a spring 42 tending to position the switch arm 39 down 40 against the contact heads 37 and 38. Connected to this switch arm 39 and extending downwardly through the base of the contactor 32 is an operating rod 43. This rod 43 extends downwardly from the contactor 45 and is connected to the semaphore signals 44 by means of a pivoted rod 45 and a joint 46. The rods 45 are so connected to the semaphore signals 44 that when the signal is in 50 danger or horizontal position the rod 43 will pull the switch arm 39 down against the contact heads 37 and 38.

In the use of multiple semaphore signals, they are only designed to stop a train when all the signals are in horizontal or danger 55 position. As shown in Figure 5, in the case of a single semaphore the joint or collar 46 is secured to the rod 43 so as to positively connect the contact heads 37 and 38 in the danger or red position and to break this contact when a semaphore is swung around to yellow or green position, the letters "R", "Y" and "G" in Figure 5 denoting red, yellow and green, respectively. In the case of 60 the multiple semaphore system the joints 46 are preferably movable on the shaft 43 and

collars 47 are secured to this shaft 43 and so positioned thereon as to be just above the joints 46 when the rods 45 are in their lowest or danger position. Thus, if any one of the multiple semaphores 44 are turned to the 70 caution or safety positions "Y" or "G" the switch plate 39 will be raised to break the contact between the contact heads 37 and 38. The operating rod 43 is preferably of a non-conducting material or may be suitably insulated from the switch bar 39. 75

As shown in Figures 4 and 6, the contactor 32 may be arranged in a horizontal position at a point adjacent one of the points of a track switch 50. An operating 80 arm 48 is connected to the knife bar 39 and extends horizontally through the base of the contactor to a definite point just inside the rail 49. This rod 48 is so positioned that the switch point 50 when in closed position 85 will move the rod a sufficient amount to disconnect the contact heads 37 and 38 but which is also so positioned that when the switch point 50 is for any reason open just enough to cause any danger to a train passing 90 over the switch, the bar 48 will be released a sufficient distance to allow the spring 42 to press the knife bar 39 against the contacting heads 37 and 38 and thus cause the rail 28 and the third rail 27 to be 95 connected with a source of current supply 30.

In the operation of this automatic train control apparatus in connection with the semaphore signal being thrown to danger or 100 closed block position, the operating rod 43 of the contactor 32, Figures 2 and 5, will be drawn down to its lowest position to form a contact between the contact heads 37 and 38, and thus connect the third rail 27 and 105 the track rail 28 with a common source of current supply 30. In case an oncoming train passes a semaphore block the trolley 25 of the train will strike the charged third rail 27 and will be swung back to form contact with the contact finger 22. This forming 110 of a contact between the third rail 27 and the contact finger 22 will cause the current from the battery 30 to pass through the wire 23, through the solenoid 5 and thus 115 complete the circuit through the wire 21 to the track 28. The energizing of the solenoid coil will cause the solenoid core 8 to be drawn inwardly to positively open the valve 14, thus releasing the air in the air 120 brake system and setting the brakes. Furthermore, this inward movement of the solenoid core will cause a seal 66 attached to the stem 7 to be severed or broken, thus requiring the engineer to make a report 125 explaining the stopping of the train and the reasons therefor.

In the operation of the automatic train control apparatus in connection with the track switch controlled contactor 32, if for 130

any reason the track switch 50 is open in advance of an oncoming train the operating arm 48 of the contactor will cause the switch arm 39 to be pressed against the contact heads 37 and 38. This closing of the circuit between the contact heads will connect the third rail 27 and the main rail 28 with a common source of current supply 30 so that the trolley 25 of the oncoming train will 10 strike the third rail 27 and will likewise complete the circuit through the solenoid operated valve to positively release the air brake pressure and stop the train.

In connection with this train control and 15 third rail system, I have provided cooperating apparatus for automatically preventing rear end collision of two trains. Preferably positioned between a standard rail 28 and the third rail 27 I have provided a series of 20 fourth rails 51 as clearly shown in Figures 7 and 8. These fourth rails 51 are of a definite length, preferably about fifteen hundred feet, and are separated from each other only by a sufficient space to break contact 25 between them. Separate third rails 52 in alignment with the aforementioned third rails 27 are preferably arranged at points opposite the breaks in the fourth rails. Looking in the direction of the arrow, each 30 fourth rail is connected by means of a wire 53 to a third rail 52 which is preferably positioned at the first fourth rail intersection to the rear of said fourth rail. By inspection of Figure 7, for example, it will be apparent that a fourth rail 51^a is connected by 35 means of a wire 53^a to a third rail 52^a.

Adapted to ride on the successive fourth rails is a trolley 54 preferably carried by a rear coach or caboose 55. This trolley 54 is 40 preferably connected and pivoted by means of arms 56 and 57 to a sliding collar 58. This sliding collar 58 is connected to a suitable governor 59 and is adapted to slide on a vertical governor shaft 60, which is rotated by rotation of the truck axle 61 and by any suitable connecting means such as a belt 62 and bevel gears 63. The coach or caboose is preferably provided with double trolleys 54 so that one of the trolleys 54 will 45 always be operable to contact with the fourth rails 51 irrespective of direction or position of the coach or caboose. Truck wheels 61 and the trolleys 54 are connected by suitable wires to a source of current supply 64 carried by the train. The governor 59 may be adjusted for different kinds of 50 trains and so designed that when the train is running below a certain speed or has stopped the trolleys 54 will either ride or rest upon a fourth rail 51 and thus connect its respective third rail 52 with the current supply 64. This governor may also be dispensed with or adjusted so that the trolley 54 will ride on the fourth rails at all 55 times.

In the operation of the automatic train stopping mechanism as controlled from the train itself, a stopping of the train for any reason or the slowing down of the train below a definite fixed speed will cause the 70 trolley 54 to be lowered against a fourth rail 51. This lowering of the trolley against the fourth rail will connect the fourth rail 51 and its connected third rail 52 and the track rail 28 with a common source of current 75 supply 64 carried by the train. In case the train is at a standstill a single fourth rail 51^a and its respective third rail 52^a will be charged so that the trolley of any oncoming 80 train will strike the charged third rail 52^a and thus complete the circuit through the solenoid 5 to operate the solenoid valve and thus release the air pressure and stop the train. In the case of a relatively slow moving 85 train each successive fourth rail and its respective third rail will be successively charged as the rear of the train is passing over these respective fourth rails, and thus any oncoming train approaching at a faster speed towards the rear of the slow moving 90 train will be stopped when its trolley 25 strikes the third rail charged by the trolley 54 of the slow moving train.

It will be understood that the automatically charged third rail may be placed in 95 any position relative to a semaphore signal, a track switch or any danger point so as to positively stop a train going at any speed within a safe distance of the danger point. It will further be understood that the fourth 100 rails will always be placed on one side of the track and that in case of a single track system third rails will also be placed on the opposite side of the track, to contact with the trolleys of any train moving in the opposite direction, and connected with the fourth rails as by means of a wire 65 as 105 shown in Figure 7. It will also be understood that each fourth rail may be connected to a respective third rail and positioned a 110 definite distance in front of the fourth rail, so as to positively prevent any danger of a "head-on" or "rear-end" collision of trains advancing or backing up in opposite directions. 115

It will be seen that I have provided a novel and very simple type of train control apparatus of a very rigid and compact construction and adapted to positively control and protect the train at all times. It will further be noted that my contactor switch may be easily connected with and operated by any normal track switch and so designed as to positively charge a third rail if for any reason the track switch is open and which will automatically disconnect the third rail from the source of current supply when the track switch is normally closed.

It will further be noted that this contactor may be connected with any standard sema- 120 125 130

phore system and is so constructed and designed as to positively charge a third rail and thus positively stop the train in case the engineer passes by a semaphore when it is set at closed block or danger position.

It will further be obvious that with my apparatus all trains properly equipped will be operated with positive and automatic safety at all times and will be positively stopped by any dangerous track condition or closed block irrespective of weather conditions or human control. It also will be obvious that after a train is once stopped by my automatic apparatus the engineer cannot again start the train until he has descended to the ground and manually restores the solenoid valve to its normal position.

Having thus described my invention, what I claim is:

20 1. In a train control system, the combination of a solenoid operated valve to effect setting of the brakes, a third rail and a track rail connected with an open circuit and a pivoted trolley carried by the train for completing the circuit from the third rail to the track rail when the circuit is closed, said trolley being so pivoted to the train that the train may back up past said charged third rail without completing the circuit.

30 2. In automatic train control apparatus, a solenoid operated valve for effecting setting of the brakes, a third rail, means carried by the train for connecting said valve and said third rail and a semaphore operated contact-

35 tor resiliently opposing the operation of said semaphore for normally connecting said third rail and one of the track rails with an open circuit and closing said circuit when the semaphore is at danger position.

40 3. In an automatic train control system, an electrically operated valve disposed in the air brake system of the train including a solenoid, a casing, a differential valve mechanism disposed in said casing, a core, and a toggle mechanism connecting said core with said valve mechanism, said valve mechanism being held in closed position by the air pressure of the air brake system except when said solenoid is energized.

50 4. In automatic train control systems, means operable by completing the circuit between a third rail and the track for setting the brakes, fourth rails of a definite length connected to said third rails and means carried by said train connecting with a current supply and adapted to contact with said fourth rails whereby said track and third rails will be connected with said current supply so as to positively stop an approaching train similarly equipped.

55 5. In automatic train control systems, means operable by completing the circuit between a third rail and the track for setting the brakes, fourth rails of a definite length connected to said third rails and means car-

ried by said train connecting with a current supply and adapted to contact with said fourth rails whereby said track and third rails will be connected with said current supply so as to positively stop an approaching train from either direction similarly equipped.

6. In automatic train control systems, a fourth rail, means connecting said fourth rail with a third rail, means carried by the train adapted to strike said third rail and to set the brakes when said third rail is charged, and means carried by the train for connecting said fourth rail and said third rail with a current supply.

7. In automatic train control systems a third rail, means carried by the train for contacting with said third rail, means connected with said first named means for automatically stopping the train when said third rail is charged, a fourth rail connected with said third rail and governor actuated means carried by the train for connecting said fourth rail and said third rail with a source of current supply.

8. In automatic train control apparatus, means carried by a train for stopping the train when said means strikes a rail and governor controlled means carried by the train for controlling the charging of said rail and an additional rail for stopping an approaching train when the speed of said first train drops below a predetermined limit.

9. In automatic train control apparatus, means carried by a train for stopping the train when said means strikes a rail and means carried by the train for so controlling the charging of said rail and another rail that said train will stop any oncoming train.

10. Train control apparatus comprising means carried by the train for stopping the train and means connected to and operable by a track switch for automatically rendering said first named means effective when said switch is open and when said train is moving in one direction only.

11. In automatic train control systems, a track, and third and fourth rails of definite lengths, the train control solenoid operable when the track and said third rail are in circuit, and train carried means operable through said fourth rail for establishing a circuit between said third rail and said track.

12. In combination with a train control system of a brake pipe; a casing, a connection between said casing and said pipe, a valve in said casing, toggle levers connected with said valve, means whereby the pressure within said casing will maintain said levers in either of their extreme positions, third rails, and means carried by the train and positioned to contact with said third rails for moving said levers.

13. In an automatic train control system, means carried by the train for effecting setting of the brakes, a third rail, means carried by the train for connecting said first named means and said third rail, a semaphore operated contactor effective to close a circuit between said third rail and one of the track rails and a series of semaphores connected to said contactor in such a manner that any one of said semaphores will be effective to open said contactor when in safety or cautious position. 35
14. In combination with a train control system, a track switch, a third rail, a contactor actuated by said switch for controlling the connection of said third rail and said track rail with a current supply, and means carried by the train for contacting with said rail and adapted to conduct any current from said third rail to said track when the train is going in one direction only. 40
15. In a train control system the combination of a solenoid operated valve to effect setting of the brakes, a third rail and a track rail arranged to complete a circuit through said solenoid, and a trolley carried by the train and positioned to contact with said third rail, said trolley being so arranged as to conduct any current from the third rail to the solenoid when moving in one direction but to be unaffected by any current in the third rail when moving in the opposite direction. 45
16. In automatic train control apparatus a solenoid operated valve for effecting setting of the brakes, a third rail, a semaphore operated contactor for electrically connecting said third rail and a track rail and means carried by the train for connecting said valve and said electrically controlled third rail, said means being so arranged whereby the train may back up past said semaphore operated third rail without actuating said solenoid operated valve. 50
17. In automatic train control apparatus a solenoid operated valve for effecting setting of the brakes, a track rail, a third rail, means for controlling the charging of said third rail and means carried by the train for contacting with said third rail to control the actuation of said solenoid, said means being adapted when moved in one direction by contact with the third rail to actuate the valve and when moved in the opposite direction by the third rail to have no effect on said valve. 55
18. A train control apparatus comprising automatically charged means positioned along the track and means carried by the train for contacting with said first named means to stop the train, said means being effective to stop the train when going in one direction only. 60

In testimony whereof I hereby affix my signature.

GEORGE W. EDWARDS.
